UNITED STATES PATENT OFFICE.

JOHN E. CAREY, OF EAGLE GROVE, IOWA, ASSIGNOR OF ONE-HALF TO
F. J. WILL AND LYMAN MOATS, BOTH OF SAME PLACE.

NECK-YOKE CENTER.

SPECIFICATION forming part of Letters Patent No. 349,383, dated September 21, 1886.

Application filed January 23, 1886. Serial No. 189,441. (No model.)

To all whom it may concern:

Be it known that I, JOHN E. CAREY, a citizen of the United States, residing at Eagle Grove, in the county of Wright and State of Iowa, have invented certain new and useful Improvements in Neck-Yoke Centers, of which the following is a specification.

The object of my invention is to provide a neck-yoke with a metallic center-piece which shall be strong, durable, practically noiseless, and capable of being easily and quickly attached to the carriage-pole and of retaining such attachment in case of accidents.

The invention consists in the peculiar construction and arrangement of the device to the ends above mentioned, as will be hereinafter fully and in detail set forth.

In the accompanying drawings, forming a part of this specification, Figure 1 represents a side elevation of the invention; Fig. 2, a plan view of the same; Fig. 3, a longitudinal section thereof, and Fig. 4 a similar view of a modified form of the part which connects with the pole.

Similar letters of reference indicate corresponding parts.

In the use of the ordinary neck-yoke center several objections present themselves. One of the most common is the tendency of the neck-yoke to strike the pole with a disagreeable slapping sound whenever the team trots. It also tends to wear out the pole, and as composed of leather is of itself subject to rapid wear, requiring to be often replaced when put to continual use, as in the case of livery vehicles. Still another objection, and one common to all the neck-yoke centers with which I am familiar, is the ease with which they are detached from the pole in case of the breakage or disconnection of a trace, resulting in the dropping of the front end of the pole and the danger incident thereto, especially in the case of a runaway. All these difficulties I seek to avoid in this invention.

Referring to the drawings, A represents a thimble or collar corresponding in general to the shape of the front end of the pole E. The rear end of this collar is beveled so as to match the collar or ring e on the pole. From the lower side of the collar extend lugs A', between

which is pivoted a latch, D, adapted to engage with the ring e. At the opposite end of the latch from the hook is an extension, d, which serves as a finger-piece whereby to disengage the hook. Above this finger-piece, and to the body of the collar, is secured a spring, b, which holds the catch in position. This spring should be made quite strong, so that in case of the accidental breakage or uncoupling of a trace the latch will hold the neck-yoke from slipping off the pole and the danger from that source be prevented. In this respect the peculiar form and position of other parts of the device afford material aid to the spring, as will be herein-after explained. To prevent the latch from becoming disengaged from the spring the former is provided with a suitable seat, as represented in Fig. 3, and a cross-bar, d', above the spring, as therein shown. On the upper side of the collar is formed a plane circular seat, to which is fitted the swivel B, connecting with the neck-yoke F. A pivot-bolt, e, holds the two parts together, in connection with the nut f. The forward part of the swivel-plate is preferably recessed, as shown, and the collar is provided with an inwardly-extending annular flange, a, corresponding thereto. This takes much of the strain from the bolt, as the greater part of the draft upon the parts is in an upward and backward direction. To protect the bolt from wear by the turning of the swivel-plate it is centrally chambered and a boss corresponding to the chamber is formed on the face of the collar-seat about the bolt, as shown in Fig. 3. Under the boss the collar is countersunk to receive the head of the bolt. To prevent the nut from working loose through the action of the swivel-plate the end of the bolt should be riveted down somewhat over the nut after it has been screwed up to the proper place. The swivel-plate is secured to the neck-yoke by means of rivets or bolts, as indicated. It will be observed that the attachment of the neck-yoke is somewhat above and behind the center of the swivel-plate, a line drawn through the center of the whole device representing about the line of draft thereon when in use. In the case of the breakage or detachment of a trace the neck-yoke will naturally be thrust forward, and a prying strain 100

will be brought to bear upon the pole, thus aiding the latch in holding the collar in position.

The collar is adapted to the different sizes 5 of poles by the use of a bushing of leather, *h*, as shown in Fig. 3.

The device is preferably made of malleable iron, and the swivel-plate all in one piece, as represented in the principal figures; but for 10 the sake of convenience in casting, the same may be made in two pieces, as shown in Fig. 4, and riveted together. In such case the rivet-holes tend to weaken the plate, and to compensate for this the device is provided with an 15 extra strap of iron, *B''*, riveted to the flange *B'*, and passing under the nut at the lower end. Thus constructed the device may be easily and 20 quickly applied to neck-yokes in common use, and when so attached forms a strong, safe, durable, and noiseless center.

Having thus described my invention, what I claim as new, and desire to secure by Letters Patent, is—

1. In a neck-yoke center, the combination of 25 the collar *A*, having an internal socket for the head of the pivot-bolt *c*, the swivel-plate *B*, having the neck-yoke-connecting portion *B'*,

joined to said plate only back of its pivotal center, whereby easy access may be had to the nut of the pivot-bolt from the outside, and the 30 said pivot-bolt *c*, all constructed substantially as and for the purpose set forth.

2. In a neck-yoke center, the combination of the collar *A*, having a circular seat on its upper side and a spring-latch on its under side, 35 adapted to engage with the ring of the vehicle-pole and hold said collar from displacement, the pivot-bolt *c*, with its head socketed in the interior of said collar, and the swivel-plate *B*, joined only to the back side of said plate to 40 the neck-yoke-connecting portion *B'*, leaving the front thereof open to receive the nut of the pivot-bolt, substantially as specified.

3. In combination with the swivel-plate of a neck-yoke center composed of two parts riveted together, as described, the auxiliary clip 45 *B''*, substantially as described.

In testimony whereof I affix my signature in presence of two witnesses.

JOHN E. CAREY.
